SHOE SOLE

George V. Walls, Littleton, Colo.

Application November 17, 1947, Serial No. 142,585

Term of patent 14 years

(Cl. D7—5)

To all whom it may concern:

Be it known that I, George V. Walls, a citizen of the United States, residing at Littleton, county of Arapahoe, and State of Colorado, have invented a new, original, and ornamental Design for a Shoe Sole, of which the following is a specification, reference being had to the accompanying drawing, forming part thereof.

In the drawing:

Fig. 1 is a bottom plan view of a shoe sole;

Fig. 2 is a top plan view thereof; and

Fig. 3 is a cross sectional view taken on line 3—3 of Fig. 1, showing my new design.

I claim:

The ornamental design for a shoe sole, substantially as shown.

GEORGE V. WALLS.
